(No Model.)

A. L. ROHRER.
SEARCH LIGHT.

No. 508,642.

Patented Nov. 14, 1893.

UNITED STATES PATENT OFFICE.

ALBERT L. ROHRER, OF LYNN, MASSACHUSETTS, ASSIGNOR TO THE THOMSON-HOUSTON ELECTRIC COMPANY, OF CONNECTICUT.

SEARCH-LIGHT.

SPECIFICATION forming part of Letters Patent No. 508,642, dated November 14, 1893.

Application filed June 20, 1892. Serial No. 437,271. (No model.)

To all whom it may concern:

Be it known that I, ALBERT L. ROHRER, a citizen of the United States, residing at Lynn, county of Essex, State of Massachusetts, have 5 invented a certain new and useful Improvement in Mechanism for Operating Search-Lights, of which the following is a specification.

My invention relates to electric search 10 lights, and its object is to facilitate the manipulation of the lamp, and improve the means for conducting the electric current thereto.

The lamp is so mounted as to have entire 15 freedom of revolution in both horizontal and vertical planes, the motion being effected preferably by endless belts and suitable driving mechanism. The electric connections are made through sliding contacts which permit 20 the continuous rotation of the lamp in either direction.

In the drawings, Figure 1 is a sectional side elevation. Fig. 2 shows the driving mechanism, and Figs. 3, 4, and 5 are details.

25 The search light is mounted on any suitable support, such as the pilot house of a vessel, indicated in dotted lines in Fig. 1. A stationary base plate A affords a support for a rotatable foot B which carries pedestals S in 30 which the lamp L is mounted. The base plate also contains a bearing *a* in which is journaled a hub D, which may be either secured to or formed integral with the foot B and carries on its lower end a horizontal pulley W². A belt B² passes around this pulley 35 and is led over suitable supporting sheaves W⁴ to a drum or axle G, located at any convenient point, as for instance in the pilot house, as shown. By means of suitable gearing, as W⁶, P, and a crank K, the lamp can 40 be rotated in a horizontal plane.

Journaled in the hub D is a shaft R, the lower end of which may be stepped in a bearing *b*, or otherwise supported. The shaft carries a miter gear W⁸, meshing with a similar gear W⁹ on a short horizontal shaft R' journaled in bearings carried by the foot B and having secured to its outer end a sprocket

wheel W'. A chain belt C passes around this wheel and over a similar wheel W, secured 50 upon one of the trunnions by which the lamp L is hung on a horizontal axis in the pedestals S. Motion is communicated to the shaft R by means of a pulley W³ secured thereto, and a belt B', running over sheaves W⁵ to a 55 drum G', which is driven by gearing W⁷ P' and a crank K'. By these means the lamp can be rotated in a vertical plane.

The electrical connections to the lamp are made through two contact rings O, O' arranged concentrically on its foot from which rings leads are taken up through the hollow pedestals S of the lamp, as shown. Fig. 5 shows the connection at the upper part of the pedestal to the lamp as heretofore used, that 65 is, a flexible cable E passes out through an opening near the top of the pedestal or standard and through an opening in the shell of the lamp, sufficient slack being allowed for a complete revolution of the lamp, or more. 70

An improved mode of conveying the current to the lamp is shown in Fig. 4. In this case the lead wire passes through a hollow shaft Q about which the lamp revolves, and terminates in a metal cap or contact O² in frictional contact with which is one of the lamp wires, the other wire, bearing correspondingly on the other pole of the circuit on the opposite side of the lamp. This connection allows the lamp to be revolved continuously in one 80 direction in both a vertical and horizontal plane. The connection Fig. 5, allows the lamp to be rotated continuously in a horizontal plane but only back and forth through a complete revolution in a vertical plane. 85

What I claim as new, and desire to secure by Letters Patent, is—

1. The combination with the stationary base A, of the foot B mounted rotatably thereon and carrying the pedestals S, the drum L hung on trunnions in said pedestals, the shaft R journaled in the hub D of the foot, and geared to one of the trunnions of the drum, the pulleys W², W³ secured respectively on the hub and shaft, the separate drums G, G' 95 located near each other at a distance, and

provided with operating mechanism, and the separate endless belts B' , B^2 connecting the pulleys W^3 , W^2 and the drums G' , G , respectively, substantially as described.

5 2. In a search light, the combination with the shell, of a hollow trunnion on which said shell I is mounted, and a lead wire entering said shell through said trunnion, and termi-

nating in a cap, with which the lamp wire has frictional contact, substantially as described. 10

In witness whereof I have hereto set my hand this 18th day of June, 1892.

ALBERT L. ROHRER.

Witnesses:

JOHN W. GIBBONEY,
DUGALD MCKILLOP.
